ATTYS.

UNITED STATES PATENT OFFICE.

FOREST BROMLEY, OF DECATUR, ILLINOIS.

GRAIN-DRIER.

1,254,770.

Specification of Letters Patent. Patented Jan. 29, 1918.

Application filed March 16, 1916. Serial No. 84,511.

To all whom it may concern:

Be it known that I, FOREST BROMLEY, a resident of Decatur, county of Macon, and State of Illinois, have invented certain new and useful Improvements in Grain-Driers, of which the following is a specification.

This invention relates to improvements in grain driers, and particularly to that type of mechanism disclosed in Patent No. 10 954,033, issued to L. C. Kiser, April 5th, 1910, on which this present invention is an improvement.

The object of this invention is to provide an apparatus or mechanism for drying grain 15 by passing it through a plurality of chambers or compartments and subjecting it to currents of air, either hot or cold, as desired. The air is admitted through perforated concaves along which the grain is 20 moved by means of suitable conveyers, so that at all times during its passage through the apparatus, it is subjected to the action of the air.

To the accomplishment of the foregoing 25 and such other objects as may hereinafter appear, my invention consists in the combination, construction and arrangement of parts hereinafter described and then sought to be defined in the appended claims, reference being had to the accompanying drawings forming a part hereof, and which shows merely for the purpose of illustrative disclosure, a preferred embodiment of my invention, it being understood that various 30 changes may be made in practice within the scope of the claims without digressing from my inventive idea.

In the drawings,

Figure 1 represents a vertical longitudinal 40 section of an apparatus constructed according to my invention, showing two sections, one arranged above the other;

Fig. 2 is an end elevation of the driving end of part of the apparatus shown in Fig. 1.

Referring now to the drawings, it is seen 45 that the apparatus or mechanism comprises the box or casing 1 which is substantially rectangular in shape, having the plurality of bearings 2 provided in each end in which 50 are journaled the shafts 3, each shaft having the suitable conveyer vane 4 thereon. Each boxing or casing is divided into two chambers or compartments by means of the partition 5 which extends from one end to a 55 point near the other end of the boxing or casing leaving the passage 6 from the upper

compartment, to the lower compartment. The shafts 3 are driven by means of the gear wheels 7 which mesh with each other, one of the shafts being driven by pulley 8 from 60 a source of power. Each box or casing has the supply inlet 9 and the discharge opening 10, which are located so that the grain has to completely traverse both chambers or compartments before it is discharged. 65

In order to subject the grain during its passage through the machine to the action of air currents, I provide an air compartment 11 in each chamber or compartment which has the concave upper surface 12. 70 This upper surface 12 is provided with the plurality of apertures or slots 13 which are preferably staggered, as shown. This air compartment is adapted to receive air from the suitable supply pipe 14, this air being 75 either hot or cold, according to conditions. The concave approximately parallels the curves of the conveyer so that as the grain is moved therealong by the conveyer, it will be subjected to the drying and cooling action 80 of the air currents.

I have shown how sections of these mechanisms constructed according to my invention may be arranged in multiple, it being understood that as many sections may be 85 used as desired. The supply inlet and discharge opening of the adjoining sections register so as to make a passage from one section to the other, as clearly shown in Fig. 1 of the drawings. I also provide the air 90 and steam exhaust openings 15 in the upper end of each section, whereby the steam and gas will escape.

In operation, the grain is discharged into the supply inlet 9 and is moved over the 95 concave 12 by means of the conveyer 4, being subjected to the hot air admitted through the inlet 14 and escaping through the slots or apertures 13 so that the grain is completely dried. If necessary, cold air may be 100 admitted through one or more of the pipes 14 so as to cool the grain after it is dried.

What I claim is:

1. An apparatus of the character described, including in combination a casing 105 having inlet and discharge openings, a partition within the casing dividing it into an upper and a lower compartment, said partition terminating short of the end wall so that the compartments intercommunicate, a 110 conveyer in each compartment, each of said compartments having a false bottom formed

on a concave to approximate the curve of the conveyer and to provide an air compartment therein, means for supplying air to said air compartments whereby grain is subjected to the action of the air during its passage along the false bottoms.

2. An apparatus of the character described, including in combination a casing having inlet and discharge openings, a partition within the casing dividing it into an upper and a lower compartment, said partition terminating short of the end wall so that the compartments intercommunicate, a conveyer in each compartment, an air compartment within each of said upper and lower compartments having a concave surface with apertures therethrough, connections for supplying air to said air compartments, whereby grain is subjected to the action of the air during its passage along said concave surface.

3. An apparatus of the character described including in combination, a casing, a partition within said casing dividing it into superposed compartments, said casing having inlet and discharge openings, said partition terminating short of one of the end walls of said casing to provide communication between the compartments, air compartments in each of said superposed compartments, the air compartment in the upper compartment extending from the inlet end

thereof to the end of the partition and the air compartment in the lower compartment of the casing extending from the passage provided by the partition to the discharge opening, said air compartments being provided with a plurality of apertures in their upper surfaces whereby grain is subjected to the action of the air during its passage through the casing.

4. In an apparatus of the character described, a section comprising a casing having an inlet opening in its top and an outlet opening in its bottom in alinement with each other so that a plurality of sections may be superposed one upon the other with the outlet opening of the top section registering with the inlet opening of the adjacent section below and so on, a partition within the casing dividing it into an upper and a lower compartment, said partition terminating short of the end wall so that the compartments intercommunicate, a conveyer in each compartment, each of said compartments having a false bottom formed on a concave to approximate the curve of the conveyer and to provide an air compartment therein, means for supplying air to said air compartments whereby grain is subjected to the action of the air during its passage along the false bottoms.

FOREST BROMLEY.
